CLAIM

The ornamental design for a shoe upper, as shown and described.

DESCRIPTION

FIG. 1 is a front perspective view of a shoe upper showing my new design;

FIG. 2 is a side view thereof;

FIG. 3 is a second side view thereof; and,

FIG. 4 is a top view thereof.

The broken lines immediately surrounding the photographic area represents an unclaimed peripheral boundary of the design. The broken lines showing the remainder of the shoe are for environmental purposes only and form no part of the claimed design.
